CLAIM

The ornamental design for a door with refrigerator and delivery storage box, as shown and described.

DESCRIPTION

1. Door with refrigerator and delivery storage box

1.1 : Perspective

1.2 : Front

1.3 : Back

1.4 : Left

1.5 : Right

1.6 : Top

1.7 : Bottom

1.8 : Perspective view showing the refrigerator door open

1.9 : Perspective view showing the delivery door open

1.10 : Perspective view showing the main door open

The diagonal shading lines in the reproductions are used to show the translucent material of the claimed design, and do not represent its surface ornamentation. The broken lines

(Continued)

shown in reproductions **1.8-1.10** depict portions of the door with refrigerator and delivery storage box that form no part of the claimed design.

1 Claim, 10 Drawing Sheets
